UNITED STATES PATENT OFFICE.

ALBERTA MARY FRANCES CASPAR, OF LONDON, ENGLAND, ASSIGNOR OF
ONE-HALF TO EUGENE PEARLE, OF NEW YORK, N. Y.

METHOD OF IMITATING STAINED GLASS.

SPECIFICATION forming part of Letters Patent No. 340,485, dated April 20, 1886.

Application filed March 10, 1885. Serial No. 159,354. (Specimens.) Patented in England October 11, 1884, No. 13,442.

To all whom it may concern:

Be it known that I, ALBERTA MARY FRANCES CASPAR, of London, England, a subject of the Queen of Great Britain, have invented certain new and useful Improvements in Imitation Stained Glass, of which the following is a specification, (for which I have obtained a patent in Great Britain, No. 13,442, dated October 11, 1884.)

My invention consists in applying to one or both surfaces of a continuous sheet of glass imitation leads, which are caused to adhere to the surface of the glass by the use of a suitable adhesive material, and in filling the spaces defined by the imitation leads with adhesive coloring-matter, which closely and permanently adheres to the glass. The imitation-lead lines are made in such shape as may be desired, and are applied to the glass in the shape in which they are originally made, or can be sprung or bent somewhat from their original shape at the time of application to the glass.

My invention further consists in the employment of a specially-prepared compound for application to the joints where the imitation leads meet one another to simulate the solder employed in genuine stained glass for fastening the ends of the genuine lead or zinc strips.

The imitation stained glass made by the practice of my invention is applicable, so far as I am aware, to all the purposes to which genuine stained glass can be put, and will be found durable in use, and the brilliancy and tone of the colors are lasting; and if desired, sheets of glass decorated by my process may be employed for decorative purposes in window-sashes in which ordinary glass has already been placed by cutting the sheet of decorated glass of such size as to fit snugly within the sash against the ordinary glass, and the decorated sheet of glass may be fastened in the sash by small nails, little strips of wood, or in any other suitable manner.

To carry out my invention I proceed as follows: I first select the desired design which I intend to reproduce upon the glass, or, having drawn a design on a piece of paper, I lay the glass cut to the proper size upon the paper

and then copy or follow the design, which can be seen through the glass, by attaching to the upper surface thereof, with any suitable adhesive substance, the imitation leads. These imitation leads are made from card or paste board or other like material, and are cut out and pressed by any suitable device or machine in such manner as to make them slightly convex on their upper surface and slightly concave on their under surface; and the convex surface is coated with metallic paper, or other metallic coating, the better to simulate the genuine leads. It is obvious that if economy is not specially desired the imitation leads may be made from solid metal, either lead or any other suitable metal or composition of metal, and may be cast therefrom, or cut, stamped, pressed, or otherwise formed to the desired shape and size. Sheet-lead is very suitable for this purpose, and the cementing material used to attach these metallic imitation leads to the glass may be any substance suitable for that purpose. As stated, these leads may be cut out by dies in predetermined shapes, or may be made in straight, zigzag, irregular, or curved strips, which may be sprung or bent somewhat from their original shape when applied to the glass, so as to follow the desired design exactly. Moreover, pressure may be employed in attaching them to the surface of the glass to produce close attachment by means of the adhesive material, if desired; and, if desired, the leads may be produced in the exact configuration or outline of the design by cutting the same out from a sheet of card-board or paste-board which is coated with metallic paper or, otherwise coated. If produced as last stated, however, the leads lack the convex outer surface and concave under surface, which greatly add to their efficiency. I do not limit myself, however, to the concavo-convex shape. They may be flat, if preferred.

The metallic-like outer surface may be given to the leads in any known manner, and thus they will simulate any desired metal. Lead and brass are most preferred by me, because they are most frequently employed in genuine stained glass; but other metals may be simulated in like manner. Any suitable adhesive

or cementing material may be used to adhere the leads to the surface of the glass; but I prefer for this purpose thick white lead mixed with strong driers, and preferably colored to 5 resemble the color of the metallic surface of the leads. For outside use it is especially desirable that the adhesive substance should be such as will not be affected by wet or cold and heat. The white lead and driers are very suitable for this purpose.

When the leads forming the whole of the pattern or design have been applied to the glass and dried thereon, (care having been taken to make all the joints in the leading fit 15 closely and well,) I next proceed to imitate the metallic solderings. To do this I mix a small quantity of metallic powder of the requisite color to a thick creamy consistency with spirit varnish, (usually copal gum dissolved in alcohol,) and drop sufficient of this paste from a small brush on all the joints in the work to entirely hide them. This substance settles and hardens very quickly, but while it is still damp I lightly pass over it a dry brush 25 filled with bright bronze-powder of the requisite hue, sufficient of this adhering to give an exact resemblance of the appearance appertaining to real metal solderings. When this part of the work is finished, it is advisable to 30 leave the glass for some hours to dry thoroughly before the application of the colors.

The liquid colors I usually employ are those generally used for lacquer work on tin, being anilines and varnish colors, which are translucent and in some instances transparent and rapid to dry being mixed with alcohol. Any kind of adhesive coloring-matter would, however, answer for the purpose, and where subjected to strong lights I prefer the vegetable 35 colors as being most permanent. To apply them to the glass on the reverse side to which the leads are fixed, or on the same side as preferred, I either pour or drop from a brush or stick a few drops of color on the upper 40 part of the space I desire to cover, (the plate of glass being somewhat inclined,) which space is of course denoted by the outlines of the metallic pattern on the glass, and allowing the color to spread over the space smoothly, as 45 consisting its flow with the brush or stick, if necessary. In this way I get a perfectly smooth even surface without any brush-marks or other imperfection. In fact, if properly executed, the color appears to be on the glass itself. 50 The color dries rapidly, generally becoming cloudy for a few moments before resuming its permanent brilliant appearance, and until this clouding or partial fixing of the color has taken place I am careful not to disturb the 55 glass. The glass should preferably be in a horizontal position while the colors are drying.

When all the colors have been applied and are dry, I generally apply to them a coating of thin mastic turpentine varnish to more thoroughly protect them from the atmosphere; 60 but this is not a necessity, however, and not advisable where very transparent white glass

is used, although it can be advantageously adopted where cathedral, roughened, opaque, flowered, embossed, muffled, or crackled varieties of glass are employed.

The imitation leads may be placed on both sides of the glass, if desired, of course coinciding in location on both sides, and this will be desirable where both sides of the glass will be exposed to view. The color may also be applied to both sides, but this is unnecessary. If the color be applied to the side on which the leads have been attached, they will greatly aid in such application, since they will act as little 80 dams and prevent the spreading or running of the colors together. Care must be observed, however, not to employ too much color. The best results are attained by a simple coating thereof, such as will result by "flowing" the 85 color over the glass, as above described.

The leads may be applied either before or after the colors have been applied; but I prefer to apply them before. When thus applied, they will appear as seen on the upper side of 90 the plate shown in Figure 1, and when applied after the color has been applied they will cover the line between the colors, as seen on the under side of the plate shown in Fig. 1.

Any excess of soldering material or adhesive 95 material (provided the white lead and driers have been employed as the adhesive material) may be readily removed by scraping with a knife, or if not too much solidified with turpentine; and any excess of coloring-matter too may be removed with methylated spirits of wine.

To still further vary my designs and give the effect of mosaics of frosted glass being inserted, I sometimes grind portions of the pattern into 105 opacity by rubbing them well with a glass muller dipped in damp sand until the appearance of frosted or unpolished glass is obtained. A second sheet of glass may, if desired, in 110 very exposed positions be placed upon the sheet decorated, as stated, the edges being united with any suitable cement or metallic, wooden, or other binder for the edges, preferably employing some sort of cement, however, between the edges of the glasses to prevent 115 dust and moisture from getting in between them, which would dull or obscure the brilliancy of the colors. A coating of transparent weather-proof varnish may be applied over the entire decorated surface of the glass, including the leads, if desired. This will still 120 further protect the same and add to its durability.

In the accompanying drawings the glass, leads, &c., are enlarged the better to illustrate 125 the invention.

Fig. 1 is a transverse section of a piece of glass to which my invention has been applied, and Fig. 2 is a plan view of a piece of glass broken from a decorated sheet. Fig. 3 is a plan 130 and sectioned view of a circular piece of the imitation lead.

A is the glass. B is the imitation lead. C is the metallic covering for the card-board or

pasteboard or like material from which the "lead" is made. D is the adhesive material. E is the coloring-matter, and F is the imitation solder. (Seen in Fig. 2.)

5 The coating of varnish is not illustrated, since it would simply be a very fine line over all the other parts of the surface of the color and lead, and would confuse the drawings.

10 I am aware that it is not new to apply to the surface of a single sheet of glass imitation-lead lines composed of an adhesive cement-like substance which is deposited upon the glass in lines to imitate the genuine leading, such cement-like substances being composed of cement, sealing-wax, beeswax, Burgundy pitch, and the like materials, which are applied in a plastic state and allowed to dry and harden on the glass, and the spaces between these imitation-lead lines thus formed being then 15 filled with coloring materials, and I do not lay claim thereto, my invention, so far as the leads are concerned, consisting in first making the leads as separate and completed structures and then adhering them, as such, to the glass 20 by the employment of adhesive substance between them and the glass. By this means my glass can be made by any one by simply purchasing the leads, the cement, and the coloring materials, and without any apparatus or 25 special skill which is requisite for the manufacture of the leading material and its application to the glass by the other processes stated.

Having described my invention, I claim—

1. As a new article of manufacture, imitation stained glass consisting of a sheet of glass 35 upon the surface whereof are adhered card-board or pasteboard imitation leads, the spaces between the leads on either side of the glass being filled with adhesive coloring-matter, substantially as and for the purposes set forth. 40

2. As a new manufacture, imitation stained glass consisting of a sheet of glass upon the surface whereof are adhered card-board or pasteboard imitation leads and adhesive coloring-matter applied to the glass coinciding 45 with the leads, and a protecting coat of weather-proof varnish applied to the surface of the coloring-matter, substantially as and for the purposes set forth.

3. The herein-described concavo-convex 50 imitation lead for use in the manufacture of imitation stained glass.

200 Regent Street, London, England, February 21, 1885.
